SCREEN

Peter Warhol, Minneapolis, Minn., assignor, by
mesne assignments, to Midland Engineering
Company, St. Paul, Minn., a corporation of
Minnesota

Application December 29, 1948, Serial No. 67,786

6 Claims. (Cl. 209—401)

1

This invention relates to screens for general use in grading and sizing either loose or suspended materials or particles and particularly to a screen having a number of advantages resulting from a novel arrangement of sinuous or wave form wires defining the openings of predetermined size for the passage of material between adjacent wires.

It is an object of my invention to provide a screen having improved resistance to both wear and blinding as a result of a novel arrangement and form of coplanar wires connected together at suitable intervals.

A further and particular object is to provide a screen of the class described having high screen efficiency by reason of a diagonal disposition of either substantially square or diamond shaped openings in relation to the direction of movement of the material along the face of the screen.

Other objects will appear and be more fully pointed out in the following specification and claims.

Referring to the accompanying drawing which illustrates my invention by way of example and not for the purpose of limitation:

Figure 1 is a plan view showing a fragmentary portion of a screen embodying my invention and wherein the sinuous wires are connected together at suitable intervals by groups of cross woven wires;

Fig. 2 is a section taken on the line 2—2 of Fig. 1;

Fig. 3 is a fragmentary plan view showing an alternate form of fastening members for connecting the sinuous or wave form wires together, and

Fig. 4 is a cross section taken on the line 4—4 of Fig. 3.

In the drawing, the numeral 6 indicates a multiplicity of similar wires of sinuous, undulated or wave form disposed substantially in a common plane. Each of these wires has a succession of substantially straight portions connected together by oppositely bent portions. Openings 7 through which the material to be screened may pass are defined by adjoining wires 6 which have the convex sides 8 of their bent portions in close proximity or substantially in contact, one with another. As shown, substantially square openings 7 are formed by approximately right angular bends in the wires 6 and the openings are diagonally disposed relative to the sides and ends of the screen.

In Figs. 1 and 2 groups of cross wires 9 are shown interwoven with the wires 6 at suitable

intervals to connect the wires 6 together as a strong screen fabric. The several groups of wires 9 are spaced longitudinally of the wires 6 at intervals greater than the length of the several openings 7 and to leave a plurality of the openings 7 in each row open and unobstructed between adjacent groups of fastening wires 9. For some purposes it may be desirable to spot weld or otherwise fasten the cross wires 9 to the several sinuous wires 6. As illustrated, there are five unobstructed openings 7 in each row between adjacent groups of wires 9, but it will be understood that these groups of wires or other cross ties may be otherwise spaced along the wires 6, as required to impart adequate strength to the screen fabric. The wires 9 are formed and arranged to retain the wires 6 side by side substantially in a common plane and with the reaches of the wires 6 between groups of wires 9 free to vibrate individually.

For the alternate form of the invention shown in Figs. 3 and 4, narrow metal bands 10, extending crosswise, are welded or otherwise rigidly secured at suitable intervals to the several wires 6. These bands may be extended across the front and back surfaces of the wires 6, in pairs, with the wires 6 between the bands 10 of each pair, as shown in Fig. 4, or the bands 10 may be spaced along the wires 6 and secured to one face thereof only. They are preferably spot welded to the wires 6 at suitable points, e. g. at the contacting points of the angularly bent portions of the wires 6 along the median line of each band 10 and/or at points along the margins of the bands 10. By this arrangement of fastening members the several wires 6 are securely held in substantially a common plane and there is a minimum of obstruction to the passage of undersize particles of the material being treated through the openings 7.

In use, the screen is preferably arranged so that the material to be screened is passed in a general direction longitudinally of the wires 6 and across the fastening members 9 or 10 so that the material moves in a direction diagonal to the substantially rectangular openings 7. The wires 6 may be held under tension longitudinally by suitable means well known in this art and the natural resiliency of the individual wires and tension therein tends to cause the wires 6 to be spaced one from another slightly at the convex sides 8 of the several angular bent portions. This allows each wire 6 to vibrate laterally in the plane of the screen as well as perpendicularly thereto along the reaches of these

wires extending between adjacent groups of wires 9 or between the longitudinally spaced fastening bands 10. Such vibration has the effect of dislodging particles which would otherwise lodge in the openings 7 and cause blinding. Consequently, my screen openings remain open under adverse conditions which would cause detrimental blinding of ordinary screens.

By disposing the openings 7 diagonally to the direction of movement of the material along the screen, screen efficiencies are improved. Efficiency is further improved by reason of my coplanar arrangement of the sinuous wires 6. The angle of the bend of these wires may be varied depending on the slope or pitch of the screen surface. For example, where the screen is to be used at a fairly steep incline, the angle or degree of bend of the several bent portions may be made somewhat obtuse to thereby afford diamond shaped openings having their longer diagonals extending longitudinally of the direction of movement of the material over the screen surface.

Unusual resistance to wear is obtained by my provision of a minimum number of members extending across and projecting above the screen surface defined by the coplanar sinuous wires 6. It will be evident that my improved screen may be furnished in a wide range of sizes, having openings corresponding generally to the range of sizes afforded by conventional woven wire screens for the grading and sizing of minerals and other materials in either dry state or in suspension in a liquid.

While the sinuous members defining either substantially square or diamond shaped openings are preferred, it is feasible to eliminate the straight portions of the wires by forming each of them with a succession of substantially semi-circular bends of alternately opposite curvature where substantially circular openings are preferred.

Having described my invention, what I claim as new and desire to protect by Letters Patent is:

1. A screen comprising, a multiplicity of sinuous wires disposed substantially in a common plane and defining openings for the passage of material, each of said wires having a succession of alternating, oppositely bent portions the convex sides of which are disposed closely adjacent to the convex sides of the adjacent wires to form between each wire and each of the adjacent wires a row of substantially separate openings for the passage and sizing of material and fastening means connecting said wires together at intervals spaced longitudinally thereof to leave a multiplicity of said openings between adjacent fastening means.

2. A screen comprising, a multiplicity of sinuous wires disposed substantially in a common plane and defining openings of predetermined substantially uniform size for the passage and sizing of material, each of said wires having alternating oppositely bent portions and the convex sides of the bent portions of adjacent wires being disposed in close proximity one to another, whereby a row of substantially separate openings are formed between each wire and each of the adjacent wires and means connecting said wires together at intervals spaced longitudinally thereof.

3. A screen comprising, a multiplicity of sinuous wires disposed substantially in a common plane and defining openings of predetermined substantially uniform size for the passage of

material, each of said wires having substantially straight portions alternating with oppositely bent portions, the convex sides of the several bent portions of each wire being disposed in close proximity to the convex sides of the adjacent wires to substantially separate the several openings between wires and means connecting said wires together at intervals spaced longitudinally thereof to leave unobstructed for the passage of material therethrough a multiplicity of said openings between adjacent connecting means.

4. A screen comprising, a multiplicity of sinuous wires having substantially straight portions connected by angularly bent portions, lying substantially in a common plane and defining substantially rectangular openings diagonally disposed to the direction of travel of material along the screen, the convex sides of the several bent portions of each of said wires being disposed closely adjacent to the convex sides of the adjacent wires to substantially separate the several openings formed by said wires and means connecting said wires together laterally.

5. A screen comprising, a multiplicity of sinuous wires lying substantially in a common plane and forming openings for the passage of material between adjacent wires, each of said wires having a succession of alternating, oppositely bent portions the convex sides of which are disposed closely adjacent to the convex sides of the adjacent wires to form between each wire and each of the adjacent wires a row of substantially separate openings for the passage and sizing of material and groups of cross wires interwoven with said sinuous wires and connecting them together laterally at intervals spaced longitudinally of the sinuous wires distances greater than the longitudinal dimension of the several openings.

40 6. A screen comprising, a multiplicity of sinuous wires lying substantially in a common plane and forming openings of predetermined size and shape for the passage of material between adjacent wires, each of said wires having a succession of alternating, oppositely bent portions the convex sides of which are disposed closely adjacent to the convex sides of the adjacent wires to form between each wire and each of the adjacent wires a row of substantially separate openings for the passage and sizing of material and substantially flat fastening members extending across opposite surfaces of said wires and connecting them together laterally at intervals spaced longitudinally of the sinuous wires distances greater than the longitudinal dimension of the several openings.
